UNITED STATES PATENT OFFICE.

FRANK M. WRIGHT, OF TOPEKA, KANSAS.

BATH-TUB ATTACHMENT.

1,148,424.

Specification of Letters Patent. Patented July 27, 1915.

Application filed February 13, 1915. Serial No. 8,116.

To all whom it may concern:

Be it known that I, FRANK M. WRIGHT, citizen of the United States, residing at Topeka, in the county of Shawnee and State of Kansas, have invented certain new and useful Improvements in Bath-Tub Attachments, of which the following is a specification.

This invention relates to an improved bath tub attachment and the principal object of the invention is to provide a device which can be connected with the faucet of a bath tub and lead the water from the faucet to a point adjacent the bottom of the tub and to also provide improved means for preventing the flow of water through the outlet pipe and for preventing soap or other material from getting into the outlet pipe when emptying the tub.

Another object of the invention is to so construct this improved device that it may be very easily assembled and to so construct it that there will be no danger of leakage.

Another object of the invention is to so construct this device that there will be no sound of splashing water when the tub is being filled.

Another object of the invention is to so construct this device that the plunger carrying the stopper may be removed if it is desired to obtain access to the outlet pipe for any reason.

This invention is illustrated in the accompanying drawings, wherein:

Figure 1 is a view showing the tub in cross section with the faucet attachment shown in elevation. Fig. 2 is a fragmentary view showing the tub in section and the attachment partially in vertical section and partially in side elevation. Fig. 3 is a bottom plane view of the housing through which the plunger head passes with part of the bottom wall thereof broken away. Fig. 4 is a sectional view taken along the line 4-4 of Fig. 1. Fig. 5 is a sectional view taken along the line 5-5 of Fig. 1. Fig. 6 is a bottom plane view of the stopper carried by the plunger head. Fig. 7 is a top plane view of the bracket carried by the conduit pipe and slidably mounting the plunger of this attachment.

The tub 10 may be of any suitable construction and is provided with a threaded opening 11 shown in Fig. 2 and also with openings to receive the supply pipe connected with the hot and cold water faucets

12 and 13 which are connected with a common outlet spout 14. These supply pipes for the faucets 12 and 13 have not been shown since they form no part of this invention, the only essential element being the water supply faucets and drain pipe 15.

The drain pipe 15 is positioned beneath the outlet opening 11 of the tub 10 and is provided with a collar or a shoulder 16 upon which the rubber gasket or washer 17 fits and which is engaged by the internal shoulder 18 of the union or coupling 19. It will thus be seen that when the union 19 is screwed tight upon the spout 20 leading from the plate 21 the gasket will provide a tight joint between the spout 20 and drain pipe 15 and the gasket 22 placed between the plates 21 and bottom of the tub will form a tight joint around the spout. By this construction water will be prevented from leaking out of the tub when the tub is filled and water will be prevented from leaking at the junction of the drain pipe and spout 20 when the stopper 23 is raised out of engagement with the spout. From an inspection of Fig. 2 it will be readily seen that the inner wall of the spout tapers thus forming a conical valve seat in which the stopper fits to form a tight closure. It should also be noted that this plate 21 is provided with an annular wall 24 having teeth 25 which permit water to pass over the plate and out through the spout but prevent soap and other objects from passing over the plate and stopping the spout.

It is desired to lead the water from the nozzle 14 of the spigot from a point adjacent the bottom of the tub and therefore the conducting pipe or conduit 26 has been connected with the nozzle 14 by means of the union 27. From the nozzle 14 the conduit 26 extends downwardly to a point adjacent the bottom of the tub where it is screwed into the socket 28 extending from the upper wall 29 of the housing 29. This housing 29 extends about the plate 21 and is provided with the depending wall 30 positioned in spaced relation to the wall 24 of the plate 21 with one portion cut away as shown in Figs. 2 and 4 to permit the water in the tub to pass out rapidly when emptying the tub. The cuff 31 of the housing 29 extends above and below the upper wall thereof and has its lower end connected with the flooring 32 of the housing, the flooring being provided with a depending wall 33 positioned between

the wall 30 and wall 24. This wall 33 is also provided with a cutout portion positioned in alignment with the cutout portion of the wall 30 to permit the water to pass rapidly out of the tub when the stopper is raised. From an inspection of Fig. 2 it will be readily seen that this housing by being constructed as shown is provided with a chamber 34 which receives the water from the conduit 26 and is provided with a reduced annular outlet slot permitting the water to pass freely out of the chamber but preventing the water from splashing in the tub as it passes out of the housing.

15 The plunger head 35 which is carried by the operating rod or handle 36 is slidably mounted in the hollow bushing 37 and is provided with a reduced neck 38 upon which the stopper 23 is placed and secured by 20 means of the nut 39. This bushing 37 is releasably mounted in the sleeve 31 and is releasably held in place by the set screw 40, the outstanding flange 41 engaging the upper edge of the sleeve or cuff 31 to suspend the 25 bushing within the same and limit the downward movement of the bushing. In order to slidably mount the plunger or rod 36 there has been provided a bearing bracket 42 which is rigidly mounted upon the conduit 26 and provided at its free end with a loop 43 and a hook 44 positioned above the loop or ring 43. This hook 44 is provided so that the pin 45 carried by the plunger 36 may be engaged by the hook to releasably hold the plunger in the raised position 35 shown in Fig. 2 and thus hold the stopper 23 out of engagement with the valve seat.

When it is desired to fill the tub the plunger is grasped by the knob 46 and turned 40 to move the pin 45 out of engagement with the hook 44 and the plunger is then pressed downwardly until the stopper is brought into tight engagement with the valve seat 20. The faucets 12 and 13 are then turned 45 on the desired amount and the water will pass through the nozzle 14 into the conduit 26 down which it will pass until it enters the housing 29. As the water enters the chamber 34 of the housing 29 it will fill this 50 chamber and will then pass out of the same through the annular slot 47 provided between the walls of the housing and into the body portion of the tub. The water will therefore flow out into the tub very close 55 to the bottom thereof and will make no splash while the tub is being filled. This will be especially true after the tub has been filled a sufficient distance to cover the walls of the housing above the height of the 60 flooring 32. When it is desired to empty the tub the plunger will be drawn upwardly and then turned so that the pin 45 will engage its hook 44 and the water will then flow out of the tub through the slot of the 65 wall 24 and through the spout 20 into the

drain pipe 15. Of course the most of the water will pass out through the broken portions of the inner and outer walls 33 and 30 of the housing 29 but to a certain extent it will enter the outlet spout 20 from all 70 directions across plate 21. As stated before the teeth of wall 24 will prevent soap or other objects from passing across the plate 20 and thus prevent the outlet spout from being stopped up.

If for any reason it is desired to obtain access to the drain pipe or if it is desired to renew the stopper 23 the said screw 40 can be removed and the hollow bushing 37 can then be drawn upwardly out of the 80 cuff 31 by simply drawing the plunger upwardly thus bringing the stopper into engagement with the lower face of the hollow bushing and forcing the bushing out of the cuff. The new stopper can then be put 85 in place or a cleaning instrument thrust through the drain pipe.

What is claimed is:—

1. A tub attachment comprising a housing having a chamber provided with a reduced outlet, a plate provided with an upstanding wall fitting within said housing, an outlet spout leading from said plate and forming a valve seat, a bushing carried by said housing above said valve seat, a stopper fitting 90 into said valve seat, a plunger slidably mounted in said bushing and carrying said stopper, a conduit pipe communicating with the chamber of said housing, and means for slidably connecting said plunger with said 95 conduit pipe.

2. A tub attachment comprising a housing having a chamber formed therein and provided with an outlet, a valve seat inclosed by said housing and provided with baffling 105 means, a conduit communicating with the chamber of said housing, a plunger slidably connected with said housing and conduit and positioned in operative relation to said valve seat, closure means moved into and out of engagement with said valve seat by said plunger, and means for releasably holding said plunger in a raised position.

3. A tub attachment comprising a housing provided with a chamber having inner 115 and outer walls positioned in spaced relation to provide an outlet, a valve seat inclosed by the inner wall of said housing, a perforated wall inclosing said valve seat and positioned within the inner wall of said housing, a closure for said valve seat, means for moving said closure into and out of operative relation with said valve seat, and a conduit communicating with the chamber of said 120 housing.

4. A tub attachment comprising a hollow valve seat, a perforated wall surrounding said hollow valve seat, a housing inclosing the wall of said valve seat and provided with a chamber having an outlet positioned 130

outside the wall of said valve seat, a closure for said hollow valve seat, operating means for said closure, and a conduit communicating with the chamber of said housing.

- 5 3. A tub attachment comprising a valve seat, a housing inclosing said valve seat and provided with a chamber having an outlet, a plunger slidably connected with said housing, a closure for said valve seat carried by 10 said plunger, a bearing, means releasably holding said plunger in an adjusted position relative to said bearing to releasably hold said closure out of engagement with said valve seat and a conduit communicating 15 with the chamber of said housing.

6. A tub attachment comprising a valve seat, a housing inclosing said valve seat and provided with a chamber having an outlet, 20 baffling means inclosing said valve seat, a conduit communicating with the chamber of said housing, a plunger slidably connected with said housing, a stopper carried by said plunger and fitting into said valve seat, a bearing bracket carried by said conduit and 25 engaging said plunger to slidably connect the same with said conduit, supporting means carried by said bearing bracket, and means carried by said plunger for engaging said supporting means to releasably hold 30 said plunger in a position to retain said stopper out of engagement with said valve seat.

7. A tub attachment comprising a valve seat, baffling means inclosing said valve seat, 35 a housing inclosing said baffling means and provided with a chamber having an outlet

positioned outside said baffling means, a conduit communicating with the chamber of said housing, a closure for said valve seat, operating means for said closure, means for 40 connecting said operating means with said conduit, and means for releasably holding said operating means in a position to hold said closure out of engagement with said valve seat.

8. The combination of a receptacle having an outlet opening, a hollow valve seat extending into the outlet opening of said receptacle, a housing inclosing said valve seat and provided with a chamber having an 50 outlet opening, said housing being positioned in spaced relation to the valve seat, a faucet for admitting fluid into said receptacle, a conduit leading from said faucet and communicating with the chamber of 55 said housing, a closure for said valve seat, and operating means for said closure.

9. A tub attachment comprising a valve seat, a housing inclosing said valve seat and positioned in spaced relation thereto, said 60 housing being provided with a chamber having an outlet opening, baffling means extending about said valve seat, a closure for said valve seat, a conduit communicating with the chamber of said housing, and operating means for said closure. 65

In testimony whereof I affix my signature in presence of two witnesses.
